COMBINATION ENVELOPE OPENER AND
PAPER SHEET CUTTERVictor Kobler and Werner Kobler,
Zurich, SwitzerlandApplication May 31, 1950, Serial No. 165,166
In Switzerland May 31, 1949

2 Claims. (Cl. 164—59)

1

Envelope openers are known in the art, representing a kind of paper cutter adapted to cut only a very narrow strip off the envelope so as not to cut the envelope contents. For such purpose a stop is fixed to one of the two knife blades of the opener, which prevents the envelope from slipping too far under the cutting edge. Such stop, however, prevents the use of the envelope opener for other paper-sheet cutting operations.

Our present invention eliminates such latter disadvantage in that the said stop is removably, preferably hingedly disposed, and means are provided for swinging the stop into the position for envelope-opening purposes and out of such position for other paper-sheet cutting operations.

In order to provide an unimpeded passage of the paper sheets between the knife blades, the drive for the vertically reciprocable knife conveniently is disposed in the movable portion of the apparatus.

One embodiment of our present invention is illustrated, by way of example, in the accompanying drawing, in which—

Fig. 1 shows the apparatus in front elevation,
Fig. 2 is a horizontal section on the line II—II
of Fig. 3,

Fig. 3 is a vertical section on the line III—III
of Fig. 2,

Fig. 4 is a cross-section on the line IV—IV of
Fig. 1, in which the envelope stop is in its operative position,

Fig. 5 is a view similar to Fig. 4, wherein the envelope stop is in the inoperative position, and

Fig. 6 is a cross-section of the bed on the line VI—VI of Fig. 1.

The apparatus has an elongated stationary bed or base 1 to each end of which a post 2 is fixed by means of a circular foot plate 2a, screws 2b and a central screw 3. The vertically movable head of the apparatus is constituted by a beam 5 which is guided by means of end housings 5a and 5a' on said posts 2. The said housings are of annular cross-section, accommodating in their bores 4 the posts 2, and are slotted at S for a purpose to be described later.

To the forward, raised pedestal portion 1a of bed 1 a horizontal knife blade 6 is secured, which co-operates with a vertical knife blade 8 which is attached to beam 5 by means of screws 18. The two blades 6 and 8 are substantially at right angles to each other, but the angle included between the two blades preferably is made slightly larger than 90°, as will be appreciated from Figs. 4 and 5 in which the blade 8 is slightly inclined with respect to the front face of beam 5 due to

formation of the groove in the face of the beam to which it is attached.

The horizontal blade 6 by means of screws 9 is movably secured at both ends to pedestal 1a. Such hold-down means are shown in Fig. 6 for one blade end. A pin 10 depending into a hollow space 11, is secured to the underside of blade 6 by means of screw 9. A disc 12, having a central aperture of larger diameter than pin 10, divides the space 11 into an upper and a lower chamber. A helical compression spring 14 surrounds the pin 10 in said lower chamber, intermediary of disc 12 and a cotter 13 passing through the end of the pin. The spring 14 draws the blade 6 down against the pedestal 1a. A screw 15 projects into the upper chamber of space 11, and a helical compression spring 16 surrounds the screw 15 and acts radially onto the pin 10 in order to push the blade 6 resiliently against the blade 8.

The movable head or beam 5 is hollow and closed at the rearside by a wallplate 17 secured thereto by means of screws 18.

The drive means for moving the beam 5 up and down, is disposed inside beam 5, with the exception of the operating lever 27. The said means comprise two levers 21 and 22 which are toothed at the ends and pivoted on a pin 19 and 20 respectively, to beam 5. The said levers are interengaged by their inner arms, while their outer arms engage the posts 2 by means of the rack portions 23 thereof. A follower flat 24 is rigidly secured to pin 19 and at both ends is engaged by studs 25 which are fixed to lever 21. Outside the beam 5 and its rear wallplate 17, which latter is traversed by the pin 19, a hand-lever 27 is secured to pin 19 by means of a pin 26. On depressing the lever 27, the beam 5 is depressed also, by virtue of the levers 21 and 22 being rocked, thus giving rise to a cutting action of the blades 6 and 8.

The posts 2 are of annular cross-section, and a helical compression spring 28 is disposed in the said posts and in the housings 5a and 5a'. The springs 28 abut at one end against the upper end of the fastening screws 3 and at the other end against the closed top of the said housings. The two springs 28 tend to push the beam 5 back into its initial position on releasing the hand-lever 27. The topmost and bottommost positions of beam 5 are defined by the lower and upper ends respectively of said slots S in the wall of the said housings, against which ends the levers 21, 22 abut in their terminal positions.

A projection 30, flush with the cutting edge of

blade 6, is provided at one end of blade 6 and contacts the blade 8 when the latter is in its top-most position. Since the blade 6 is resiliently engaged to the blade 8, the said projection causes an accurate agreement of the two blade edges on those ends thereof at which the cutting operation is initiated.

In close proximity and rearwardly of knife blade 8 a stop is disposed, which comprises two strips 31 and 32. An envelope E (Fig. 4) put up 10 against the said stop can only be cut for the slight width by which the stop is separated from the cutting edge. The said width may be defined as desired by the thickness of the selected front strip 31. The two strips 31, 32 are interconnected 15 by means of screws 33. The holes in strip 32 through which screws 33 project may be made slightly larger than the diameter of screw 33 or may be made in form of slits, which arrangement on assembly permits adjusting the stop 20 strip 31 in different positions on strip 32 and thereby accurately to the cutting edge of blade 8. The strip 32 is hingedly connected at 34 to the beam 5. The stop 31, 32 thus may be swung 25 counterclockwise from its operative position shown in Fig. 4 into the non-operative position shown in Fig. 5, in which latter case the opener may be used as cutter for a paper-sheet P.

The stop 31, 32 may be swung into and out of its operative position by manipulating a knob 35 which is provided with a shank or stem 36. In Figs. 1 and 4, the said stop is shown in the operative, and in Fig. 5 in the inoperative position. The stem 36 is recessed at 36a for engagement with the ceiling of beam 5. An inclined helical-tension spring 37 at one end is attached to a screw 38 which is secured to beam 5, and at the other end to a clip 39 which is secured to stem 36. The lower end of stem 36 is pivotably engaged in an eyelet 40 fixed to the rearside of strip 32. The stem 36 projects through an aperture 5b in the ceiling of beam 5. In Figs. 1 and 4, the stem 36 is engaged to the said ceiling by means of recess 36a. By pushing knob 35 in Fig. 1 to the left, the stem 36 is disengaged from the said ceiling and raised relatively to the latter by the action of spring 37, whereby the stop 31, 32 is swung into the inoperative position shown in Fig. 5.

A rearwardly projecting bed extension 41 of 50 which the underside is flush with that of bed 1, is provided on the side of handlever 27, which prevents a rearward tipping of the apparatus on actuating the hand-lever 27. A ridge 42 is provided on the rearward portion of bed 1 for the purpose of preventing the cut-off waste paper 55 from dropping from the apparatus.

Within the scope of our present invention, constructions different from that shown are feasible. The stop 31, 32 could be made detachable instead of swingable. Further, the said stop could be attached to the lower portion of the apparatus, resiliently abutting against the knife blade 8 of the upper portion of the apparatus so as to follow the movement thereof. In such latter case, means would be provided for retaining the stop in that position in which the paper sheets could pass unhindered when the apparatus is not used for opening envelopes.

What we claim as new and desire to secure by Letters Patent is:

1. Stop means for a paper sheet cutter having a stationary portion with a horizontal knife blade affixed thereto and a vertically movable beam with a substantially vertical knife blade affixed thereto, for cooperating with said horizontal knife blade, comprising a hingedly mounted stop on the movable beam of said cutter, said stop being disposed in close proximity to and rearwardly of the vertical knife blade and comprising two strips interconnected side by side, a knob for manually pivoting said stop into and out of operative position projecting from said beam, a shank integral with said knob and engaging said stop in pivoted relation, said shank having a recessed portion adapted to engage said beam, a spring attached at one end to said beam and at the other end thereof to said shank, said knob when depressed swinging said stop into operative position and the recessed shank portion engaging said beam and the spring being tensioned in a direction to lock the stop in said position, said stop when in operative position lying in a plane parallel to said vertical knife blade.

2. Stop means for a paper sheet cutter as claimed in claim 1, said movable beam of said cutter comprising a hollow casing of rectangular cross section, said stop being hingedly connected to the underside of said casing.

VICTOR KOBLER.
